United States Patent Office.

ISAIAH KINGMAN, OF WALTHAM, MAINE.

Letters Patent No. 94,612, dated September 7, 1869.

IMPROVEMENT IN JOINT STANDARD-SLEDS

The Schedule referred to in these Letters Patent and making part of the same.

To all whom it may concern:

Be it known that I, ISAIAH KINGMAN, of Waltham, in the county of Hancock, and State of Maine, have invented a new and valuable Improvement in Joint Standard-Sleds; and I do hereby declare that the following is a full, clear, and exact description of the construction and operation of the same, reference being had to the annexed drawings, making a part of this specification, and to the letters and figures of reference marked thereon.

Figure 1, of the drawings, is a top view of my invention.

Figure 2 is a rear view of the front pair of runners.

Figure 3 is a longitudinal vertical central section of my invention.

Figure 4 is a rear view of the rear pair of runners.

My invention relates to the manufacture of sleds; and

It consists, mainly, in a novel arrangement of devices intended for use in adapting the runners of a sled to the inequalities of the ground over which it may be drawn.

My sled is constructed with four short runners, of the form shown on the drawings, and marked respectively A and B, upon which I arrange the body-frame C, in the manner represented.

The letters a represent the knees of my sled, pivoted to the runners respectively, and formed with cross-heads, that serve as rests for the cross-bars D and E.

The letter e represents a rod, arranged in staples upon the front side of cross-bar D, and adapted to serve as a pintle for the hinges, next mentioned. This rod is made removable by a nut and screw on one end thereof.

The letters e represent arms, hinged upon the rod e, as shown, and also hinged to the front end of runners B by the staples and pins h.

The letters i represent braces, attached respectively to the inner sides of arms e, and hinged to the rod c by a staple-joint; and the letters n represent bars, that serve as rests for said springs.

The letters o represent blocks, affixed to the upper sides of runners B, to serve as stops in preventing too great depression of said runners.

The front part of my sled is provided with the devices above described, as appertaining to the rear part thereof, except the blocks o, and inasmuch as the front cross-bar of the frame C is a rocker operating upon the cross-bar E, the front knees a are made shorter than those arranged for the rear, and the staples h are also of less length than those of the rear.

The neap of my sled is attached to the rod c, and also to the cross-bar E, as shown, and it is held firmly in place by the brace s.

The letter y represents the double-tree, pivoted in the neap, and to which the team is attached.

A sled constructed in the manner herein described, is adapted for use upon uneven ground, and may be moved with but little jolting over those inequalities in snow-paths, which are always formed by moving heavy loads thereon.

What I claim as my invention, and desire to secure by Letters Patent, is—

The sled herein described, having runners A and B, knees a, rods c, arms e and n, braces i, staples h, and blocks o, constructed and arranged substantially as specified.

In testimony that I claim the above, I have hereunto subscribed my name, in the presence of two witnesses.

ISAIAH KINGMAN.
